STOCK GRIPPER WITH REMOVABLE PADS

John M. Ingalls, Windsor, Vt., assignor to Cone Automatic Machine Company Inc., Windsor, Vt., a corporation of Vermont

Application August 11, 1944, Serial No. 549,043

11 Claims. (Cl. 279—51)

1 This invention relates to stock grippers such as collets or pushers which are suitable for grasping lengths of stock either while machining operations are being performed on those portions of the stock projecting from the collets, or for feeding the stock endwise, and relates particularly to such grippers as are provided with removable pads on their inner faces, adapting such a gripper to take stock of various sizes and cross sections as desired, depending upon the interior size and configuration of the pads.

An object of the present invention is to provide cooperating constructions of jaws and pads and pad-retaining means such that the pads are easily removed and replaced and when in position are so securely retained that stock may be rigidly held by the gripper.

A further object is to provide pad retaining means movable to hold or release the pads by angular motion about the gripper axis.

A still further object is to so form the retaining means that the torque exerted on the stock during machining operations tends to hold the retaining means in securing position.

Still another object of the invention is to provide means readily accessible for moving the retaining means between securing and releasing positions and for retaining the securing means in securing position.

A further object is to provide a means for securing the retainer which when actuated to secure the retainer will also insure that the retainer is in tight retaining position.

A further object is to provide constructions by which the pads are interchangeable between the jaws of each gripper so that any pads of a set can be assembled with any jaw of the gripper for which the set is designed to cooperate.

This application is a continuation-in-part of my application Serial No. 496,604, filed July 29, 1943, for Stock gripper with removable pads.

For a more complete understanding of this invention, reference may be had to the accompanying drawings in which

Figure 1 is a side elevation partly broken away and in section on line 1—1 of Figure 2 of a collet with pads, constructed in accordance with this invention.

Figure 2 is a front end elevation of the same.

Figure 3 is a perspective view showing the forward end of the collet, the pads and retainers being removed.

Figures 4 and 5 are perspective views of a pad retaining element and a pad, respectively.

Figure 6 is a detail sectional view on line 6—6

2 of Figure 1 and showing the pads locked in position.

Figure 7 is a view similar to Figure 6, but showing the pads unlocked in condition for removal.

Figure 8 is a detail sectional view on line 8—8 of Figure 6.

Figure 9 is a view similar to Figure 8, but showing the securing means in fully secured position and with the retainer in tight retaining position.

Figure 10 is a view similar to Figure 4, but showing a modification.

Referring to the drawings, which show the pads applied to a collet of the spring jaw type, at 1 is indicated the tubular collet having spring jaws 2 formed thereon by the provision of longitudinal slots 3 extending inwardly from the forward end of the collet toward the rear end thereof, which is continuous circumferentially and is provided with internal threads as at 4 by which it may be secured to an actuating sleeve in the well known manner.

The collet jaws have their spring portions provided with the inclined or conical surfaces 5 adjacent to their free ends for cooperation with matingly tapered surfaces (not shown) on a suitable spindle within which the collet is positioned, relative axial motion of these parts then serving to flex inwardly the free ends of the spring jaws to grip the work or to permit them to expand and release the work which extends through the collet.

In order that work of various sizes and configurations may be gripped by the collet, the spring jaws are provided with removable and replaceable work-engaging pads 6. As shown the interior surfaces 7 of these pads, together form a cylindrical surface which is particularly suitable for engagement with cylindrical work, but these inner faces might be formed to define between them a square, hexagonal, or other shaped opening, depending upon the particular configuration of the stock which the collet may handle at any particular time and may be of various internal sizes to conform to the size of the stock.

The pads and the interior face of the collet are formed with inter-engaging parts shown as ribs 8 on the pads and mating longitudinal grooves 9 in the collet jaws, which retain the pads and jaws against disassembly by relative radial motion, but permit disassembly or assembly by relative axial motion. As shown each of the pads, which covers slightly less than one-third of a complete circumference of the work, is provided with two such ribs spaced apart, the remote faces 10 and 11 of these ribs flaring outwardly

radially from each other so that the pads cannot be disassembled from the collets by bodily motion of the pads toward the axis of the collet. The ribs and grooves, however, do permit axial sliding motion between the pads and the collet jaws, which thus permits these parts to be assembled or disassembled by relative axial motion. Means are provided, however, by which when the pads are in fully assembled relation to the jaws, they may be held against relative axial motion so that they are locked against disassembly. As shown such means comprises a retainer 12 for each pad, these retainers being mounted to slide angularly about the axis of the collet in transverse grooves 14 in the collet and through mating transverse grooves 15 in the pads (see particularly Figures 1, 3 and 5).

Each of the retainers, as shown best in Figure 4, is provided with a full slot 16 and a partial slot 17 through which the ribs 8 of the pads may slide when the retainer is in such angular position that the slots 16 and 17 are in registry with the ribs 8. Between the slots 16 and 17 the retainer has a retaining portion 18 and at one end a part of a similar portion 19, and when these parts 18 and 19 extend within the slots 15 of the pads in the position of Figure 6, they obstruct the relative axial motions between the pads and collet jaws and thus prevent disassembly thereof. The retainers are arranged to be held by one of the cooperating parts of the collet and as shown are retained by the collet jaws rather than by the pads. To this end, each of the collet jaws has an arcuate slot 20 opening out through its forward face and extending through into the transverse slot 14. A screw 21 rides in each of these slots 20 and is threaded through a hole 22 in one of the retainers. This screw riding in the slot 20 holds each of the retainers 12 against disassembly from the collet, but when loosened permits a sufficient relative angular motion between the retainers of the parts to permit the retainers to be moved between the positions shown in Figure 7 wherein their slots 16 are in registry with the ribs 8 of the pads which permits these pads to be assembled or disassembled by relative axial motion between the pads and the collet, and the positions of Figure 6 where the locking portions 18 and 19 are partly in alignment with the two portions of the pad ribs on either side of the slot 15, thus preventing disassembly of the pads from the collet.

By manipulation of the screws 21 so that their rear ends bear against the rear walls of the collet slots 14, as shown in Figures 1 and 8, the retainers may be pushed forwardly against the opposite walls of these slots and be thus clamped in adjusted position.

Preferably, and as shown in Figures 4, 8 and 9, the intermediate portions of the retainers are substantially thinner than the widths of the grooves 14 and 15 within which they ride and adjacent to opposite ends they are provided with pads or thickened portions 120 on their outer faces which slidably fit within the grooves 14 and 15. This construction permits flexing of the intermediate portions of the retainers by tightening of the screw 21 which passes through its intermediate portion, as shown in Figure 9, which imparts a yielding locking pressure upon the pads and jaws. However, the retainers may be of uniform thickness throughout, as shown in Figure 10, if desired. If desired, also, a tapered or conical seat 210 may be made in the back face of the groove 14 of each jaw opposite to the screw 21

when the retainer is in its fully retaining position, the sloping side of this seat 210 acting when the screw 21 is tightened to wedge the retainer into its limit of retaining position and hold it firmly against motion toward pad-releasing position. Should it be desired to remove the pads, these screws 21 are loosened so that the retainers are free to be moved in their slots, and they are then moved by pressure exerted on the sides 10 of the screws 21 to unlocking position. The pads may then be freely removed and replaced by pads of a different set which may then be locked in position by moving the retainers to their obstructing positions and then clamping them 15 against the slot walls by turning the screws 21 in the proper direction. The inner end of each screw 21 may, if desired, be slightly headed so as to prevent accidental disassembly of the screw from its retainer by too much loosening of the 20 screw, though this will not prevent sufficient motion of the screw to effect clamping or releasing of the retainers. It does, however, prevent accidental entire removal of the screws 21, which when the pads are not in position, would permit 25 the retainers and screws to become detached with the possibility of becoming lost. It will thus be seen that the retainers may be held with the collet and that the only parts which are ordinarily removable are the pads themselves. Thus no 30 elements are likely to become lost, which if lost, would interfere with the proper functioning of the mechanism. While as shown these pads are applied to a collet, it should, of course, be understood that they might be applied to a pusher or 35 any other tubular stock gripper arranged to permit pads to be assembled or disassembled with relation thereto.

From the foregoing description of one embodiment of this invention, it should be evident to 40 those skilled in the art that various changes and modifications might be made without departing from the spirit or scope of this invention.

I claim:

1. A work gripper comprising a tubular holder, 45 work-engaging pads on the interior of said holder, said pads and holder having interengaging portions permitting relative axial motion between said pads and holder but preventing radial detachment thereof, and an element rockably carried by said holder for motion laterally of said interengaging portions between an angular position obstructing said relative axial motion and an angular position not obstructing such relative axial motion.
2. A work gripper comprising cooperating parts 55 including a tubular holder and a detachable work-engaging pad on the interior of said holder, said parts having mating longitudinally extending ribs and grooves, certain walls of which flare 60 outwardly from the central axis of said holder to prevent disassembly of said parts by relative radial motion but permitting disassembly of said parts by relative longitudinal motion, said parts having transverse grooves registering when said 65 parts are in fully assembled relation, and a retainer positioned within and movable lengthwise of said transverse grooves, said retainer having a slot registering with said lengthwise ribs and grooves in one position of said retainer in which 70 position said parts may be disassembled, parts of said retainer bridging said ribs and grooves in another position of said retainer and holding said parts against disassembly.
3. A work gripper comprising cooperating parts 75 including a tubular holder and a detachable work-

engaging pad on the interior of said holder, said parts having mating longitudinally extending ribs and grooves, certain walls of which flare outwardly from the central axis of said holder to prevent disassembly of said parts by relative radial motion but permitting disassembly of said parts by relative longitudinal motion, said parts having transverse grooves registering when said parts are in fully assembled relation, a retainer positioned within and movable lengthwise of said transverse grooves, said retainer having a slot registering with said lengthwise ribs and grooves in one position of said retainer in which position said parts may be disassembled, parts of said retainer bridging said ribs and grooves in another position of said retainer and holding said parts against disassembly, and means for holding said retainer assembled with one of said parts.

4. A work gripper comprising cooperating parts including a tubular holder and a detachable work-engaging pad on the interior of said holder, said parts having mating longitudinally extending ribs and grooves, certain walls of which flare outwardly from the central axis of said holder to prevent disassembly of said parts by relative radial motion but permitting disassembly of said parts by relative longitudinal motion, said parts having transverse grooves registering when said parts are in fully assembled relation, a retainer positioned within and movable lengthwise of said transverse grooves, said retainer having a slot registering with said lengthwise ribs and grooves in one position of said retainer in which position said parts may be disassembled, parts of said retainer bridging said ribs and grooves in another position of said retainer and holding said parts against disassembly, and adjustable means for holding said retainer assembled with one of said parts, said gripper having means cooperating with said adjustable means in one adjusted position of said adjustable means to secure said retainer in one position or to release said retainer for such movement when said adjustable means is out of said adjusted position.

5. A work gripper comprising cooperating parts including a tubular holder and a detachable work-engaging pad on the interior of said holder, said parts having mating longitudinally extending ribs and grooves, certain walls of which flare outwardly from the central axis of said holder to prevent disassembly of said parts by relative radial motion but permitting disassembly of said parts by relative longitudinal motion, said parts having transverse grooves registering when said parts are in fully assembled relation, a retainer positioned within and movable lengthwise of said transverse grooves, said retainer having a slot registering with said lengthwise ribs and grooves in one position of said retainer in which position said parts may be disassembled, portions of said retainer bridging said ribs and grooves in another position of said retainer and holding said parts against disassembly, a screw projecting from said retainer through an elongated slot in one of said parts and having its opposite end adapted to contact with said one part, said screw being accessible from one end of said gripper for adjustment to hold said retainer assembled with said one part clamping said retainer in adjusted position, or to release said retainer for such movement.

6. A work gripper comprising a tubular holder, and work-engaging pads on the interior of said holder, said pads having longitudinally extending ribs and said holder having longitudinally

extending grooves into which said ribs may extend, mating longitudinal side faces of said grooves and ribs flaring outwardly from the axis of said holder to thereby hold said holder and pads against disassembly by relative radial motion thereof but permitting disassembly by relative axial motion thereof, said ribs and the stock between said grooves having transverse slots therethrough registering when said holder and pads are in operative assembled relation, pad retainers slideable within said transverse slots and having slots therethrough through which said ribs may pass when said retainer slots are in alignment with said ribs to permit disassembly of said pads from said holder and movable out of alignment with said ribs to retain said pads in position, said work gripper including means for holding said retainers in pad-locking position.

7. A work gripper comprising a tubular holder, and work-engaging pads on the interior of said holder, said pads having longitudinally extending ribs and said holder having longitudinally extending grooves into which said ribs may extend, mating longitudinal side faces of said grooves and ribs flaring outwardly from the axis of said holder to thereby hold said holder and pads against disassembly by relative radial motion thereof but permitting disassembly by relative axial motion thereof, said ribs and the stock between said grooves having transverse slots therethrough registering when said holder and pads are in operative assembled relation, and pad retainers slideable within said transverse slots and having slots therethrough through which said ribs may pass when said retainer slots are in alignment with said ribs to permit disassembly of said pads from said holder and movable out of alignment with said ribs to retain said pads in position.

8. A work gripper comprising a tubular holder, and work-engaging pads on the interior of said holder, said pads having longitudinally extending ribs and said holder having longitudinally extending grooves into which said ribs may extend, mating longitudinal side faces of said grooves and ribs flaring outwardly from the axis of said holder to thereby hold said holder and pads against disassembly by relative radial motion thereof but permitting disassembly by relative axial motion thereof, said ribs and the stock between said grooves having transverse slots therethrough registering when said holder and pads are in operative assembled relation, pad retainers slideable within said transverse slots and having slots therethrough through which said ribs may pass when said retainer slots are in alignment with said ribs to permit disassembly of said pads from said holder and movable out of alignment with said ribs to retain said pads in position, and means for holding said retainers assembled with said holder.

9. A work gripper comprising a tubular holder, and work-engaging pads on the interior of said holder, said pads having longitudinally extending ribs and said holder having longitudinally extending grooves into which said ribs may extend, mating longitudinal side faces of said grooves and ribs flaring outwardly from the axis of said holder to thereby hold said holder and pads against disassembly by relative radial motion thereof but permitting disassembly by relative axial motion thereof, said ribs and the stock between said grooves having transverse slots therethrough registering when said holder and pads are in operative assembled relation, pad retainers slideable within said transverse slots and

having slots therethrough through which said ribs may pass when said retainer slots are in alignment with said ribs to permit disassembly of said pads from said holder and movable out of alignment with said ribs to retain said pads in position, said work gripper including means for holding said retainers in pad-locking position, said retainers having screws threaded thereto and movable in slots in said holder for holding said retainers assembled with said holder and adjustable to clamp said retainers in pad-holding adjusted positions or to release said retainers.

10. A work gripper comprising cooperating parts including a tubular holder and a detachable work-engaging pad on the interior of said holder, said parts having mating longitudinally extending ribs and grooves, certain walls of which flare outwardly from the central axis of said holder to prevent disassembly of said parts by relative radial motion but permitting disassembly of said parts by relative longitudinal motion, said parts having transverse grooves registering when said parts are in fully assembled relation, a retainer positioned within and movable lengthwise of said transverse grooves, said retainer having a slot registering with said lengthwise ribs and grooves in one position of said retainer in which position said parts may be disassembled, portions of said retainer bridging said ribs and grooves in another position of said retainer and holding said parts against disassembly, a screw projecting from said retainer through an elongated slot in one of said parts and having its opposite end adapted to contact with said one part, said screw being accessible from one end of said gripper for adjustment to hold said retainer assembled with said one part clamping said retainer in adjusted position, or to release said retainer for such movement, said retainer being thinner intermediate to its end portions than at said end portions and through which intermediate portion said screw extends to be flexed on

8
the tightening of said screw to thereby exert clamping pressure of said retainer against said pads and holder.

5 11. A work gripper comprising cooperating parts including a tubular holder and a detachable work-engaging pad on the interior of said holder, said parts having mating longitudinally extending ribs and grooves, certain walls of which flare outwardly from the central axis of said holder to prevent disassembly of said parts by relative radial motion but permitting disassembly of said parts by relative longitudinal motion, said parts having transverse grooves registering when said parts are in fully assembled relation, a retainer positioned within and movable lengthwise of said transverse grooves, said retainer having a slot registering with said lengthwise ribs and grooves in one position of said retainer in which position said parts may be disassembled, portions of said retainer bridging said ribs and grooves in another position of said retainer and holding said parts against disassembly, a screw projecting from said retainer through an elongated slot in one of said parts and having its opposite end adapted to contact with said one part, said screw being accessible from one end of said gripper for adjustment to hold said retainer assembled with said one part clamping said retainer in adjusted position, or to release said retainer for such movement, said one part having a tapered socket to receive said opposite end of said screw in position to wedge said retainer laterally of the axis of said screw toward a limit of pad-retaining position.
